UNITED STATES PATENT OFFICE.

ROBERT E. HINES, OF NEW YORK, N. Y., ASSIGNOR TO NEW JERSEY SILK MACHINERY COMPANY, OF PATERSON, NEW JERSEY, A CORPORATION OF NEW JERSEY.

SPINNING, DOUBLING, AND TWISTING MACHINE.

1,423,801.

Specification of Letters Patent. Patented July 25, 1922.

Application filed August 9, 1921. Serial No. 490,868.

To all whom it may concern:

Be it known that I, ROBERT E. HINES, a citizen of the United States, residing at New York city, in the county of New York and 5 State of New York, have invented certain new and useful Improvements in Spinning, Doubling, and Twisting Machines, of which the following is a specification.

This invention relates to spinning, doubling and twisting machines, and it has for its 10 principal object to improve machines of this class of the particular kind set forth in the Seymour Patent No. 909,466; other objects will appear hereinafter.

15 In the drawings,

Figure 1 is a sectional view on line 1—1, Fig. 2;

Figure 2 is a front elevation of a spinning, doubling and twisting unit;

20 Figure 3 is a section on line 3—3, Fig. 10;

Figure 4 is a fragmentary side elevation of what is shown in Fig. 3;

Figures 5 and 6 are sectional details of the feed pulley;

25 Figure 7 is a front elevation and Figure 8 a front-to-rear section of the spindle group, the section of the latter figure being on line 8—8, Fig. 9;

Fig. 9 is a plan of the spindle-group;

30 Figure 10 is a plan of the two assembled arms for the spinning spindles; and

Figures 11 and 12 show the respective arms in plan and side elevation.

The two spinning spindles are designated 35 1 and the twisting spindle is designated 2, 3 being the spindle rail in which a number of groups of spindles 1 and 2 will be mounted. The whirls of these spindles are arranged so that the driving belt A passes between them,

40 or back of spindle 2 and in front of spindles 1. The flanged socket 4 affording a support for spindle 2 may be held in rail 3 in the usual way, as by nut 5^a and spring 6^a on its depending tubular shank 4'. The annular part 5' of

45 a bracket 5 projecting rearwardly from the rail rests on and is pinned (at 5'', Fig. 8) to the rail, being penetrated by shank 4'. Between this and the flange 4'' of the socket are journaled, also penetrated by said shank, the 50 bearing portions 6' of arms 6 which at their free annular ends 6'' carry the flanged sockets 7 and thereby form supports for the spindles 1, the shanks 7' of which sockets are

held in said annular ends 6'' by the nuts 8 and springs 9. Such support for one spindle 1 has journaled therein on a vertical axis a roller 10 to bear against the front face of the belt. When the supports for the spindles 1 swing forward the whirls of the spindles 1 will press the belt against the whirl of spindle 2, and when they swing back the whirls of spindles 1 clear the belt, which is also then withdrawn from the whirl of spindle 2 by the roller 10. Annular part 5' of bracket 5 is embraced by the coils of a spring 11 which is kept from turning thereon by having an eye 11' formed therein engaged by a lug 5''' on said part, the ends of the spring being engaged in suitable holes 6''' in the arms 6: this spring tends to hold the arms 70 pressed forward, so that the spindles will be driven (position of Fig. 9).

An upright rod 12 is guided at its lower end in the bracket 5, being subject to the upward pressure of a spring 13 interposed between the bracket and a casting 14 on the rod having arms 14' which project under the whirls of the spindles and may act thereon as brakes, Fig. 9, said casting forming in effect a cam-fork by having depending converging pins 14'' which slide more or less freely in holes 6'''' in the arms 6; the upper end of the rod is guided in a slot 15' of the fixed bracket 15 and has a shoulder 12' to catch under the bracket and hold 85 down the rod against the tension of spring 13. When the rod is down it permits the spring 11 to hold the arms 6 pressed forward, so that the spindles will be driven; when the rod is released and rises under the 90 pressure of spring 13 the convergent pins of its cam-fork retract the arms 6, clearing the spindle whirls from the belt.

The threads extend up from bobbins on the spindles 1, by which they are spun, 95 through individual guides 16 on rod 12, then back of and over guides 17 on bracket 15, then through the eyes of individual fallers 18 and back over a common guide 17' on said bracket, then, being now doubled, down and 100 (with one or more turns) around the feed pulley 19, then through a guide 20 on the rod, and finally through a traveller 21 which runs on a ring 22 on the suitably reciprocated ring-rail 22', being wound on the bobbin on spindle 2, of course after undergoing 105

twisting together. The pulley, which is mounted on the rod to rotate in a vertical plane, has formed or otherwise caused to rotate with it a pinion 23 which overhangs and is adapted when the rod is in the locked-down position to mesh with a pinion 24 driven by the suitably rotated constantly going horizontal shaft 25 on which is fixed a tappet or trip member 26. On a horizontal axis 27 (on which the fallers are pivoted) there is pivoted in the rod a dog or lever 28 whose longer or heavier arm has a rearwardly and downwardly beveled end 28' and normally holds the dog upright (position of Fig. 1) and whose other arm has a horizontal stud 28'' opposite the fallers. The dog may swing into contact with a stop 28''' (Fig. 1) on rod 12 when a faller, being released by the breaking of its thread, falls and so actuates the dog, and in this position the beveled end of the dog will be struck by tappet 26, so that the rod will be forced forward and, its shoulder being disengaged from bracket 15, be then elevated by spring 13, thus to clear pinion 23 from pinion 24, so that the draft on the thread is discontinued, and withdraw the spindle whirls from contact with the belt. To re-set the parts the operator, after piecing together the ends of the thread and reestablishing it in working relation to the feed pulley and faller, leaving the latter held up by the thread as before, has only to push the rod down and back into re-locked relation to bracket 15. The extent of upward movement of the rod is determined by contact of adjusting nuts 14''', screwed on the rod, with the bracket 5. It will be noted that when the rod is in locked-down position it is in effect clamped between the spring 13 and bracket 15, so that a quite definite gear-relation is maintained between the pinions 23 and 24. Also that the device 26 has nothing to do with actually moving the spindles clear of the belt; this function is performed by the spring 13, which, moreover, maintains a certain control over the rod when the operator moves it to resetting position. These are factors considerably increasing the efficiency of the machine.

To insure proper gripping on the thread the feed pulley 19 has the novel construction illustrated in Figs. 5 and 6, where the gear 23 is incidentally shown as an integral part of it. The pulley, which is a metal die-casting, is formed with a hub 19^a, a disk-like body part 19^b, and a rim 19^c which latter forms lateral flanges at both sides, the flange at one side having the teeth of gear 23 and the flange at the other side have circumferential ribs 19^d forming a V-shaped groove to receive the thread. Recesses 19^e are formed at regular intervals in the latter flange, opening laterally into the same and communicating with the groove, and in these are driven

inserts 29 of yielding thread-gripping material, such as cork, upon which the thread bears. These inserts add greatly to the tractive action of the pulley, and when worn may be readily replaced. Further, the rim-flange 70 containing these inserts may have an undercut 30 communicating with the groove and adapted to receive a knife or hook as shown in Fig. 6, whereby to either cut or catch and break a coil of thread that may be left wound 75 on the pulley and would be otherwise difficult to remove on account of the narrow V-shaped groove.

Having thus fully described my invention, what I claim as new and desire to secure by Letters Patent is:—

1. In combination, a spindle, a support therefor, a pair of spindles, a pair of supports for said pair of spindles pivoted concentrically with the first support, a driving belt arranged between the first spindle and the pair of spindles, and means to move the pair of supports back and forth together in reverse directions to cause the spindles to grip the belt or clear the same. 90

2. In combination, a spindle, a support therefor, a pair of spindles, a pair of supports for said pair of spindles pivoted concentrically with the first support, a driving belt arranged between the first spindle and the pair of spindles, and a spring urging 95 the pair of supports each in the direction to cause said pair of spindles to coact with the first spindle to grip the belt.

3. In combination, a spindle, a support therefor, a pair of spindles, a pair of supports for said pair of spindles pivoted concentrically with the first support, a driving belt arranged between the first spindle and the pair of spindles, and means to move the 100 pair of supports back and forth together in reverse directions to cause the spindles to grip the belt or clear the same including a spring extending around the first support and engaged with and normally urging each 105 of the other two supports in one direction.

4. In combination, a spindle, a support therefor, a pair of spindles, a pair of supports for said pair of spindles pivoted concentrically with the first support, a driving belt arranged between the first spindle and the pair of spindles, a spring urging the 110 pair of supports each in the direction to cause said pair of spindles to coact with the first spindle to grip the belt, and means to move said pair of supports each in the opposite direction. 115

5. In combination, a supporting structure, an upright spindle, a support for the spindle movable in said structure, a belt to drive 120 the spindle toward and from which said support is movable substantially horizontally, means to move said support toward and from the belt including an up-and-down movable device having a cam to engage the 125

support and normally urged but held by said structure against movement in one direction and also movable to clear said structure, and means, controlled by the thread, to move 5 said device clear of said structure.

6. In combination, a supporting structure, an upright spindle member, a belt member to drive the spindle member, one of said members being movable into and normally held 10 in contact with the other, an up-and-down-movable device normally urged but held by said structure against movement in one direction and also movable to clear the same, said device having means when so moved to 15 cam one of said members away from the other and also means to brake the spindle member, and means, controlled by the

thread, to move said device clear of said structure.

7. In combination, a supporting structure, 20 a driving element journaled therein on a horizontal axis, an up-and-down-movable device normally urged in one direction and normally held against movement in said direction by said structure but movable to 25 clear the latter, a thread feed pulley in gear with said element when said device is so held against movement by the frame, and means, controlled by the thread being fed by the pulley, for transmitting movement from said 30 element to said device to disengage the latter from said structure.

In testimony whereof I affix my signature.
ROBERT E. HINES.
